STRINGED MUSICAL INSTRUMENT

Theodore M. McCarty, Kalamazoo, Mich., assignor to Gibson, Inc., Kalamazoo, Mich., a corporation of Michigan

Application June 20, 1957, Serial No. 46,674

Term of patent 14 years

(Cl. D56—9)

Fig. 1 is a top plan view of a stringed musical instrument showing my new design, and

Fig. 2 is a side elevational view thereof.

The back of the article is substantially plain.

I claim:

The ornamental design for a stringed musical instrument, as shown and described.
